CLAIM

The ornamental design for a tape dispenser, as shown and described.

DESCRIPTION

FIG. 1 is a front perspective view of the tape dispenser showing my new design.

FIG. 2 is a view of the left hand side of the tape dispenser of the present invention;

FIG. 3 is a view of the left hand side of the tape dispenser of the present invention;

FIG. 4 is a top view of the tape dispenser of the present invention;

FIG. 5 is a bottom view of the tape dispenser of the present invention;

FIG. 6 is a front view of the tape dispenser of the present invention; and,

FIG. 7 is a rear view of the tape dispenser of the present invention.

The broken lines shown in FIGS. 1-3 represent surface indicia and forms no part of the claimed design.
